UNITED STATES PATENT OFFICE

127,743

DESIGN FOR A PIN OR SIMILAR ARTICLE

Einar L. Christensen, Los Angeles, Calif., assignor of thirty-five per cent to Adolph Boehm and twenty-five per cent to Austin Sherman, both of Los Angeles, Calif.

Application March 25, 1941, Serial No. 99,869

Term of patent 7 years

To all whom it may concern:

Be it known that I, Einar L. Christensen, a citizen of the United States, residing at Los Angeles, in the county of Los Angeles, State of California, have invented a new, original, and ornamental Design for a Pin or Similar Article, of which the following is a specification, reference being had to the accompanying drawing, forming a part thereof.

The characteristic features of my design for a pin, or similar article, reside in the ribbed face plate substantially as shown.

I claim:

The ornamental design for a pin or similar article, as shown and described.

EINAR L. CHRISTENSEN.
